UNITED STATES PATENT OFFICE.

EDWARD C. MIX, OF LONG BEACH, CALIFORNIA.

SANITARY KNEADING-BOARD.

1,151,895.

Specification of Letters Patent. Patented Aug. 31, 1915.

Application filed May 4, 1914. Serial No. 836,382.

To all whom it may concern:

Be it known that I, EDWARD C. MIX, a citizen of the United States, residing at Long Beach, in the county of Los Angeles and 5 State of California, have invented a new and useful Sanitary Kneading-Board, of which the following is a specification.

My invention relates to molding and kneading boards as used in kitchens for 10 making bread, cutting meat and kindred purposes, and has for its object the provision of means for rendering such boards sanitary in every respect and obviating the necessity for cleaning and scraping the boards after 15 use, which consists, primarily, in spreading paper or parchment over the upper surface of the board in such a manner that it may be held firmly in contact with the board and removed and destroyed after use, the paper 20 or parchment being mounted on the board in a suitable receptacle from which it may be played out from a roll or otherwise supplied to the board, as desired.

I attain the above objects by the mechanism illustrated in the accompanying drawings, in which:

Figure 1 is a perspective of a board with my device shown thereon and with certain portions broken away; Fig. 2 is a fragmentary sectional elevation on the line x^2-x^2 of 20 Fig. 1; Fig. 3 is a fragmentary sectional elevation on the line x^3-x^3 of Fig. 2; Fig. 4 is a fragmentary perspective of the paper clamp hinge; and Fig. 5 is a section of the 35 outer end of the board showing the clamp in position in the groove.

Similar characters of reference indicate the same parts throughout the specifications and the several views of the drawings.

40 In the drawings, 1 represents an ordinary molding, kneading or meat cutting board, which may be of any convenient size, and which, in my device serves as a base, upon which is mounted, at one end, a tubular housing 45 of metal and comprising two semi-cylindrical sections 3 and 4, hinged together at the back by means of a pin 5 adapted to seat in the outwardly bent hinge sections 6 on the upper member and 7 on the lower member 50 of the housing. The upper member 3 of the housing has suitable end closures 8 suitably secured thereto, and the lower member 4 has the end members 9, which, in addition to forming a closure for lower member, extend down to and are secured to the side of 55 the board 1 by means of the screws 10, the

end members of both the upper and lower members of the housing being adapted to align and entirely close the end of the housing, except for the central perforation 11 which is formed half in one and half in the other of said end members.

A core 12 made of paper pulp or other suitable and similar material having formed on each end an annular groove 13 is adapted to be revolvably mounted in the housing, the periphery of the perforations 11 engaging the annular grooves 13 in the end members 8 and 9 and the lateral movement of the core thus prevented. A roll of sanitary paper or 70 parchment is secured at one end to the core 12 and the other end of the paper is adapted to protrude downwardly through the lateral slot 14 in the lower portion of the member 4 of the housing, the width of the paper roll 75 15 and that of that slot 14 being substantially the width of the board 1.

The metal in the vicinity of the hinge sections 6 and 7 of the two members 3 and 4 of the housing and also at the front thereof, 80 may be so formed that no dust can enter the housing and a suitable latch 16 may be secured to one of the members and adapted to latch over a suitable hook or eye 17 in the other member of the housing, and a roll of 85 paper may be either placed in position or removed by opening the housing.

The paper 15 is adapted to be drawn through the slot and sufficiently forward of the board as to completely cover the length 90 thereof and enough more to hang down slightly over the front edge, as shown in Fig. 2, and as it is necessary that the paper should be held firmly in contact with the board when the board is in use, I provide a 95 lateral V-shaped groove 18 in the top of the board, slightly in front of the housing, and a similar groove 19 in the front edge of the board, in the former of which, 18, is seated a lateral rod 20 of triangular cross 100 section whose top is substantially flush with the top of the board and to which is secured a flat, thin strip of metal 21 extending slightly forward of the groove and adapted to rest on the top of the board when the rod 105 20 is in the groove, and the groove 19 having a similar rod 22 except that it lacks the metal strip 21, and its outer surface is adapted to be substantially flush with the edge of 110 the board 1.

The rod 20 is resiliently held in the groove 18 by means of a pair of oppositely mounted

arms 23, one on each side of the board 1, pivoted to the board 1 by the screws 24 at one end and at the other rigidly secured to the rod 20 by the screws 25 and the nuts 26, a suitable spring 26 being interposed on each of the screws 24 between the arms 23 and the edge of the board 1, secured at one end to a screw 10 in the board and at the other hooked over the end of the screws 25.

10 The outer rod 22 has an eye 28 secured in one end which is hinged to a bracket 29 by a suitable pin 30, the bracket 29 is secured to the board 1 by a screw 31 and a dowel 32 adapted to seat in a suitable perforation 15 in the edge of the board to prevent its turning, and the other end of the rod has a screw 33 with a head 34 between which and the end of the rod a seat is formed to receive a hook 35 on a latch 36 secured pivotally 20 to the board 1 by a screw 37. Thus the paper 15 when drawn under the rods 20 and 22, is forced into the grooves 18 and 19 and the tension of the springs 26 at one end and the rigid clamp formed by the rod 22 and 25 the latch at the other end, and is held smoothly and in rigid contact with top surface of the board.

A suitable eye 38 may be secured to the rear edge of the board 1 for hanging the 30 board on a wall, and a similar eye 39 is secured to the top of the plate 21 and the rod 20 in order that the rod 22 and the arms 23 to which it is secured may be raised sufficiently to slip the paper under, when 35 spreading it over the top of the board.

When it is desired to use the board, the rod 20 may be raised and the end of the paper grasped and drawn forward until it 40 extends slightly forward of the end of the board, the latch 36 may be released from the rod 22, this rod swung outwardly on its pivot, the paper slipped between the rod and the end of the board, the rod forced with the paper into the groove 19 and the latch 45 hooked again over the end of the rod. After a piece of the paper has been used and a clean piece is desired, or, in the event that further use of the board is not required, the rod 22 may be released from the latch and 50 the used portion of the paper torn off against the edge of the plate 21 on the rod 20, the edge of this plate being sufficiently in advance of the groove 18 to permit the grasping of the end of the paper for further use.

55 Paper such as I intend to be used in connection with my device is frequently required in kitchens for covering butter, cakes, meats and similar articles, and when hung on the wall of the kitchen or pantry, a supply of such paper may be always available by tearing off a sufficient length from the roll 15, and without removing the board from the wall.

In the device herein described and illustrated, it is obvious that a practical, simple,

cheap and effective molding and kneading board is provided which may be used for any ordinary purpose, and being thoroughly sanitary and dust proof, the necessity for scraping and cleaning the boards is eliminated and a cheaper board may be used for all purposes. It is obvious that the structure of my invention may be changed in many particulars, according to the purpose for which it is used, without departing from the spirit of my invention, and though I am aware of several different ways of accomplishing the same result, it is thought that the structure shown and illustrated is preferable to all others, and believing the device 70 entirely novel, I desire to claim broadly thereon.

Having thus described my invention what I claim as new and desire Letters Patent for, is:

1. A sanitary kneading board provided at one end with a suitable paper receptacle having means whereby a roll of paper may be inserted therein and removed therefrom and an aperture whereby the end of the paper may be drawn through the receptacle and extended over the top surface of the board, combined resilient clamping and paper tearing means adjacent to said receptacle and rigid clamping means at the opposite end of said board for holding the paper firmly in position thereon.

2. A sanitary kneading board provided with a suitable paper receptacle at one end adapted to revolvably and removably hold a roll of paper and having means whereby the paper may be extended over the top surface of the board, resilient clamping means adjacent to said receptacle and rigid clamping means at the opposite end of said board for holding the paper firmly in position thereon.

3. A kneading board provided with a rigidly mounted transversely disposed paper receptacle at one end having a hinged top and means for holding a roll of paper, and a pair of transverse grooves, one on the top surface of the board adjacent to said receptacle and the other on the opposite end thereof; combined paper clamping and tearing means adapted to register with and resiliently hold the paper in said first mentioned groove, and rigid clamping means adapted to hold the paper in said other groove.

4. The combination with a kneading board, of a housing rigidly mounted on one end thereof provided with means for holding a roll of paper removably and revolvably therein; and a pair of parallel transverse clamping members pivotally mounted on opposite ends of said board for holding the paper from said roll when extended over the board firmly in position thereon, one of said members being resiliently and the other rigidly held when in clamping position.

5. The combination with a kneading

board, of a housing rigidly mounted on one end thereof provided with means for holding a roll of paper removably and revolvably therein; said board having a pair of parallel 5 transverse grooves, one in the forward end and the other on the top surface adjacent to said housing; a pivotally and resiliently mounted combined clamping and paper tearing member adapted to seat in said last mentioned groove; and a pivotally mounted clamping member adapted to rigidly seat in said first mentioned groove, for holding the paper firmly in position on the board.

6. The combination with a kneading 15 board, of a housing mounted on one end thereof provided with a roll of paper and holding means therefor; a pair of parallel transverse clamping members pivotally mounted on said board, one of said members adjacent to said housing being provided 20 with paper tearing means and resiliently mounted and the other member being provided with a locking means for holding it in rigid relation with said board; there being 25 transverse grooves in the board in the plane

of each of said members whereby the paper from said roll may be firmly held in position on the board.

7. In a kneading board, the combination of a board provided with a transverse groove 30 on the top surface near one end and a similar groove on the opposite end; a housing rigidly mounted thereon adjacent to said first mentioned groove and provided with a roll of paper capable of being extended over the 35 top surface of said board; a combined paper clamping and tearing member pivoted on the sides of the board and adapted to resiliently hold the paper in said groove; a clamping member in the plane of said other groove 40 pivotally mounted on one side of the board and adapted to hold the end of the paper in said groove; and means for locking said last mentioned clamping member in said groove 45 for rigidly holding the paper on the surface of said board.

EDWARD C. MIX.
